INDOOR TELEVISION ANTENNA

Arthur Baum, Teaneck, N. J.

Application April 11, 1957, Serial No. 45,692

Term of patent 7 years

(Cl. D26—14)

Fig. 1 is a front perspective view of an indoor television antenna, showing my design as mounted on the back edge of the top of a television set;

Fig. 2 is a rear perspective view of my design;

Fig. 3 is a front elevation on a reduced scale of my design, showing the portions of the antenna hidden by the set in Fig. 1; and,

Fig. 4 is a side elevational view of my design taken from the right of Fig. 1 and with part of the dependent housing broken away.

In the drawings, portions of the dipole arms of the antenna and the lead-in wires are broken away for convenience of illustration.

I claim:

The ornamental design for an indoor television antenna, substantially as shown and described.
